ALPHEUS W. ALTORFER, OF PEORIA, ILLINOIS, ASSIGNOR TO ALTORFER BROS. COMPANY, OF EAST PEORIA, ILLINOIS, A CORPORATION OF ILLINOIS

DESIGN FOR A CASING FOR A COMBINED WASHING MACHINE AND CENTRIFUGAL DRIER

Application filed March 5, 1928. Serial No. 25,706. Term of patent 14 years.

To all whom it may concern:

Be it known that I, ALPHEUS W. ALTORFER, a citizen of the United States, residing at Peoria, in the county of Peoria and State of Illinois, have invented a new, original, and ornamental Design for a Casing for a Combined Washing Machine and Centrifugal Drier, of which the following is a specification, reference being had to the accompanying drawing, forming part thereof,

The figure is a perspective view of a casing for a combined washing machine and centrifugal drier, showing my new design.

I claim:—

The ornamental design for a casing for a combined washing machine and centrifugal drier, as shown.

ALPHEUS W. ALTORFER.
